UNITED STATES PATENT OFFICE.

CARL A. LOHMAN, OF SEATTLE, WASHINGTON.

DRY-KILN.

1,294,129.

Specification of Letters Patent. Patented Feb. 11, 1919.

Application filed July 18, 1917. Serial No. 181,226.

To all whom it may concern:

Be it known that I, CARL A. LOHMAN, a citizen of the United States, and resident of the city of Seattle, county of King, and State 5 of Washington, have invented certain new and useful Improvements in Dry-Kilns, of which the following is a specification.

My invention relates to dry kilns such as are used for drying lumber.

10 My object is to produce a dry kiln in which the results produced in the operation thereof will be more efficient both in the action upon the lumber and also in the convenience of its operation.

15 My invention comprises the features which will be particularly defined by the claims.

In the accompanying drawings I have shown a dry kiln having embodied therein 20 the features of my invention.

Figure 1 is a longitudinal vertical section through a dry kiln.

Fig. 2 is a horizontal section taken through a dry kiln approximately upon the 25 plane indicated by the broken line 2—2 of Fig. 6.

Fig. 3 is a section taken upon the line 3—3 of Fig. 6.

Fig. 4 is a section taken upon the line 4—4 of Fig. 6, but which does not extend to and include the final or discharging end of the kiln.

Fig. 5 is a section on the line 4—4 of Fig. 6, showing the final or discharging end of 35 the kiln.

Fig. 6 is a cross sectional elevation through the section of the receiving end of the kiln.

Fig. 7 is a cross sectional elevation 40 through the central or main body of the kiln.

Fig. 8 is a cross sectional elevation through the final or discharging end of the kiln.

Fig. 9 is a sectional plan taken beneath 45 the floor level showing the construction of the kiln through the central portion thereof.

Fig. 10 is a sectional plan showing the construction at a level which includes the fresh air supplying flues of the discharge 50 end of the kiln.

In constructing my kiln I employ tile, concrete, brick, or other equivalent non-combustible building material for constructing the main body of the kiln. Such material 55 is used to construct what might be termed a complete kiln, containing the desired

chambers, flues, etc., and then, with this, I employ an outer casing which is preferably of wood frame construction. This forms an insulating cover for the kiln and also 60 protects it from the weather.

The kiln, as herein illustrated and de- 65 scribed, is of the type which is known as a continuous kiln; that is, the lumber is in-

serted at one end of the kiln and is ad- 70 vanced along the kiln as it dries and is re- moved from the opposite end of the kiln.

The treatment required by the lumber dur- 75 ing the process of drying should vary at dif- ferent stages. It should also vary in accord-

ance with the kind of lumber, that is, the kind of timber from which it is manufac- 80 tured. Also, in accordance with the kind

of lumber as it comes from different parts of the log and as to whether it is water 85 soaked or partly dried before sawing. There should also be a certain amount of variations in accordance with the position in the log from which the board is cut. That is, as to whether it is radial or tangential to 90 the grain. I, therefore, provide means by which the lumber may be given different treatments in accordance with the special re-

quirements.

The different sections of the kiln may be 85 called the receiving section A, which is at the end of the kiln at which the lumber is introduced, intermediate section, as B, and the final or discharging section C, which is at the end from which the lumber is re- 90 moved. The handling of the lumber in the kiln may be in accordance with the usual practice whereby the lumber is piled upon trucks and these pass over rails laid in the floor of the kiln. The main body of the kiln 95 contains a drying chamber 1 through which the lumber passes while being dried and a heating chamber 10, which is located beneath the floor of the drying chamber.

For the first or receiving section A, the 100 floor 11 of the drying chamber may be omitted, which would join the drying and the heating chambers. At this stage in the drying of the lumber, it is desirable to in- 105 ject steam directly into the kiln so the same may come in contact with the lumber. For this purpose the pipes 2, which are supported upon bars 20 extending transversely of the lower chamber 10, are provided with a cer- 110 tain number of perforations through which steam escapes into the kiln. I provide this section of the kiln with pipes or flues 12 con-

necting with the top of the drying chamber, through which portion the steam and vapors given off by the lumber at this stage, may be discharged. These flues would be controlled in their opening in any suitable manner.

Those sections of the kiln following after the first or receiving sections are provided with a floor 11 which separates the drying chamber and the heating chamber. Along one side of the kiln, outside the rail upon which the truck runs, openings 13 are formed in the floor which establish direct communication with the upper part of the heating chamber 10 and the drying chamber. This forms a flue or passage for the air from the heating chamber to the drying chamber. Similar openings are formed at the opposite side of the kiln, but a wall 15 is extended downward along the inner side of this opening so as to form a flue 14 which extends downward alongside the heating chamber to a point where it is beneath the steam pipes which are employed 20 for heating the air. At this point it communicates with the heating chamber.

The steam pipes 2 throughout all portions of the kiln excepting the receiving section A, are tight, that is, do not discharge any 30 steam directly in the kiln. They are arranged as a horizontal layer resting upon transverse bars 20. The air, which is received from the drying chamber through the flue 14, is discharged into the heating 35 chamber beneath these pipes. This air passes upwardly through these pipes and then through the flue or opening 13 into the drying chamber. These pipes being arranged in a horizontal layer, their effectiveness in heating the air is greater than if 40 they were grouped in a plurality of layers through which the air successively passed.

It will be noted that the side walls 3 of the drying chamber are slightly inclined 45 toward each other as they extend upwardly. In consequence, the space 30 which exists between the side wall of the pile of lumber and the side of the kiln, decreases in width as it goes up. It is contemplated that the 50 lumber to be dried in this kiln shall be piled in horizontal layers. The heated air coming from the pipes 2 is delivered upwardly at one side of the kiln between the side of the kiln and the pile of lumber. 55 The air withdrawn from the drying chamber to be delivered to the heating chamber, is taken from the similar space at the opposite side of the kiln. In consequence, the air will be passed horizontally between the 60 layers of lumber in the pile.

This manner of piling the lumber is a great deal more convenient than edge piling. It requires no special apparatus for holding the lumber in shape while drying. 65 The lumber may thus be piled directly upon

the trucks, using nothing in the pile excepting stickers to keep the layers of lumber apart. It has, therefore, been found a more economical method of handling the lumber than when special apparatus is required and the lumber is piled on edge. 70 Also, the weight of the superposed layers of lumber will hold those beneath them in shape to prevent warping or twisting. The gradual reduction in the cross section 75 at each side of the pile of lumber, has a tendency to compel the air to pass through the pile of lumber to the opposite side of the lumber, from which it is withdrawn to the heating chamber. 80

At the discharge end of the kiln the section C is provided with fresh air inlet flues 4, which draw outside air from the end of the kiln and discharge the same into the heating chamber through openings 40. 85 That side wall of the kiln, which is at the side from which the air is withdrawn to supply the heating chamber in the other sections of the kiln, is provided with openings 50, which communicate with vertical 90 flues 5, so that, in conjunction with the fresh air flues 4, a circulation of outside or fresh air may be established through this section of the kiln, the same being passed through the lumber and then discharged. 95 In this section of the kiln the opening which supplies the flue 14 of the other sections is omitted, the floor being continuous at this side. The corresponding opening 13 at the opposite side, which is 100 connected with the heating chamber is, however, retained. In this section of the kiln as in the other, the circulation is through the lumber, from one side of the kiln to the opposite. 105

In constructing the outer casing I employ vertical studs or posts 6, each of which is of composite construction, consisting of three beams or studs placed along inside of each other. The central member 60, of each 110 of these posts, in its upper part at least, is inclined inwardly at an angle which corresponds with the angle of inclination of the wall 3. This central member of the post need not, however, extend entirely to the 115 bottom of the kiln, but may stop substantially at the level of the floor 11, as is shown at 61, in Fig. 7.

The top of the kiln employs transversely extending joists 7 and an outer covering 70, 120 which may be of any suitable construction. The sides of the kiln are also provided with an outer skin 62, which may be of any convenient material, usually of lumber. This outer casing forms an effective insulating 125 cover for the kiln. It forms a number of pockets in which dead air is retained and thus retains the heat of the kiln. The joists 7, which support the roof, are preferably maintained at a slight elevation higher than 130

the kiln so as not to interfere with the expansion and extraction of the inner portion of the kiln by changes in temperature. This outer casing is self supporting, not relying 5 upon the inner masonry structure.

The above construction of kiln enables the lumber to be given the sort of treatment which it desires at all stages during the process of drying and enables this treatment 10 to be varied in accordance with the requirements of lumber of different qualities and of different conditions. It dries the lumber piled in the manner in which it may be most cheaply handled and provides for prevention 15 of warping and other changes due to drying.

While I have described my invention as a kiln for drying lumber, it is evident that the material being dried does not determine the 20 invention and that the kiln may be used for drying other products, such, for instance, as clay and plaster products. The principles set forth herein as applied to drying lumber are equally applicable to the drying of other 25 products.

What I claim as my invention is:

1. A continuous lumber dry kiln having a receiving section at one end provided with means for discharging steam into direct contact 30 with the lumber, a following section having an air heating chamber and air heating pipes therein and flues to produce a closed circulation through the loads of lumber, and a final cooling section provided 35 with flues and valves to produce a fresh air circulation therethrough.

2. A continuous dry kiln for lumber having a receiving section and steam discharging pipes in said receiving sections, a section 40 following the receiving section having a floor extending beneath the loads and air heating pipes beneath said floor, the spaces beneath and above said floor having circulation connections at both sides the kiln, said 45 connections being above the pipes at one side the kiln and beneath the pipes at the other side, whereby a rotary circulation passing through the lumber is secured.

3. A continuous dry kiln for lumber having a receiving section and steam discharging pipes in said receiving sections, a section following the receiving section having a floor extending beneath the loads and air heating pipes beneath said floor, the spaces beneath 55 and above said floor having circulation connections at both sides the kiln, said connections being above the pipes at one side the kiln and beneath the pipes at the other side, whereby a rotary circulation passing 60 through the lumber is secured, and a final section provided with discharge flues and air inlet flues which respectively discharge and receive the air at opposite sides of the kiln.

4. A dry kiln having a drying compartment, a heating compartment beneath the

drying compartment and heating pipes in said latter compartment, flues connecting said compartments at opposite sides of the kiln, said flues at one side of the kiln connecting with the heating compartment above 70 said pipes and at the other side of the kiln beneath the pipes, whereby a closed circulation through the lumber and crosswise the kiln is obtained.

5. A lumber drying kiln having a lumber 75 drying compartment provided with tracks for trucks, and a heating compartment beneath the drying compartment, the receiving end of the kiln having steam pipes discharging directly into the kiln, the remainder of 80 the kiln having a floor between the compartments and heating pipes therein disposed in a horizontal layer, flues connecting the upper part of the heating compartment with one side of the drying compartment and 85 flues connecting the lower part of the heating compartment with the other side of the kiln.

6. A lumber drying kiln having a lumber 90 drying compartment provided with tracks for trucks, and a heating compartment beneath the drying compartment, the receiving end of the kiln having steam pipes discharging directly into the kiln, the remainder of the kiln having a floor between the compartments 95 and heating pipes therein disposed in a horizontal layer, flues connecting the upper part of the heating compartment with one side of the drying compartment and flues connecting the lower part of the heating 100 compartment with the other side of the kiln, the discharging end of the kiln having discharging flues at one side and fresh air inlets at the opposite side.

7. A lumber drying kiln having a lumber 105 drying compartment provided with tracks for trucks, and a heating compartment beneath the drying compartment, the receiving end of the kiln having steam pipes discharging directly into the kiln, the remainder of 110 the kiln having a floor between the compartments and heating pipes therein disposed in a horizontal layer, flues connecting the upper part of the heating compartment with one side of the drying compartment and flues connecting the lower part of the heating 115 compartment with the other side of the kiln, the discharging end of the kiln having discharging flues at one side and fresh air inlets discharging into the lower 120 part of the heating compartment, and having no down draft flue connecting the two compartments.

8. A dry kiln having an inner wall composed of noncombustible material, and an 125 inclosing casing of wood construction supported independently of the inner wall.

9. A dry kiln having an inner wall composed of noncombustible building material and an inclosing casing composed of a self 130

supporting wood construction having its skin spaced outwardly from the inner wall to form air insulation.

10. A dry kiln having an inner masonry wall and an inclosing self supporting casing spaced outwardly to form air insulation between the two.

11. A dry kiln having an inner masonry wall and an inclosing casing composed of 10 posts at the sides and beams at the top and a skin secured to the outer surfaces of said posts and beams.

12. A dry kiln having an inner masonry wall and an inclosing casing composed of 15 vertical studs placed against the outer surface of the inner wall and beams supported from said posts and extending over and out of contact with the roof thereof and a skin secured to the outer faces of the posts and beams.

13. A dry kiln having an inner wall having its sides slightly inclining inward toward the top, means for delivering the heated air through the floor at one side of the 25 kiln and means for withdrawing the air through the floor at the other side of the kiln.

14. A dry kiln having side walls inclined toward each other toward the top, an air heating compartment beneath the floor of the drying compartment, a flue connecting the upper part of the heating compartment with the floor at one side of the drying compartment, and a flue connecting the lower

part of the heating compartment with the 35 floor at the other side of the drying compartment.

15. The combination with a dry kiln of an inclosing casing having its side walls composed of vertical studs and an outer skin 40 and a roof comprising beams carried by said studs and an outer roofing skin.

16. The combination with a dry kiln having an inner wall which tapers inwardly toward its top, an inclosing casing having side 45 posts each containing a vertical member and a member inclined to conform with the inclination of the inner wall, and a roof carried by said posts.

17. The combination with a dry kiln having an inner wall which tapers inwardly toward its top, and an arched top, an inclosing casing having side posts each composed of vertical members and an intermediate member inclined in conformity with the side 55 of the inner wall, and a roof having beams carried by the posts, and an outer skin upon the posts and roof beams.

18. A continuous dry kiln having inner walls provided at the discharge end of the 60 kiln with air discharge openings in a side wall, and a flue connecting with said openings, and an inclosing casing of wood frame construction having its skin spaced outwardly from the walls of the kiln proper. 55

Signed at Seattle, Washington, this 12th day of July, 1917.

CARL A. LOHMAN.
